UNITED STATES PATENT OFFICE.

JAMES FRANCIS MAYS, OF BIRMINGHAM, ALABAMA.

LISTING-MACHINE.

No. 899,229.

Specification of Letters Patent.

Patented Sept. 22, 1908.

Application filed December 5, 1905. Serial No. 290,359.

To all whom it may concern:

Be it known that I, JAMES FRANCIS MAYS, a citizen of the United States, residing at Birmingham, in the county of Jefferson and 5 State of Alabama, have invented new and useful Improvements in Listing-Machines, of which the following is a specification.

My invention relates to improvements in calculating and listing machines.

10 The leading machines in the art to which my invention pertains are operated by striking and setting the proper keys with the fingers after which a lever or crank is operated to register the numbers on the item and total 15 dials and to print or list the items. The operation of pulling or throwing the lever is not only fatiguing to the operator, but decreases very considerably the speed at which the machine can be manipulated. In other pending 20 applications I have shown and claimed a calculating machine adapted to register the items by the direct action of the keys and without the use of any lever or crank.

25 It is one object of my present invention to provide a machine which will set the type digits to print each item of figures; carry the total and set the total type digits to print it; and return the keys and other mechanism back to initial or zero position, all by the 30 mere pressure of the keys, and without the use of levers or similar devices.

It is a further object to provide such a machine with printing devices which are independent of the operation of the calculating 35 machinery and may be used at the option of the person manipulating the machine. The advantages derived from such an arrangement are of importance, for I can print items or only totals as may be desired thereby improving on those machines which have to print a list of items in order to get totals on the proper dials. I provide means to exhibit each item registered for checking against mistakes, whether the items be printed or 40 not, or, if desired, these proof figures can be dispensed with by throwing the item dials out of operation while the machine registers the movements of the keys on the total dials, thereby lightening the work and reducing the 45 resistance of the operating keys.

It is a further object of my invention to improve the printing devices, adapting them to print the items or totals by a movement of the paper carriage and without the use of a 50 ribbon or shifting of the registering dials. The printing is done at the top of the machine

and by a rapid, easy touch of the fingers, whereas in other machines this is done at the bottom or in the interior of the machine and by the laborious manipulation of a lever. 60 The item and total dials having set the type for printing, the paper carriage is depressed, by a stroke similar to that required to operate a key, and moves a small inking roll over the item type before bringing the paper into 65 contact therewith. If a total is desired the paper carriage may be readily shifted over the total dials and then depressed to print. The left hand may be used to both shift and print and at the same time these operations 70 may be carried on while the hand is used for operating keys as practically no more movement will be necessary than that required to operate the spacer key on typewriters.

When the listing or item dials are in use it 75 becomes necessary to provide means to return them to initial position after each item has been registered. This is done by a reset key which is struck after each item has been registered in the same manner as the spacer 80 key on typewriters.

My invention further comprises the details of construction and arrangement of parts hereinafter more particularly described and which have been designed and assembled 85 to produce the results above stated in the simplest and most economical manner possible.

The comparatively few parts, their cheapness of manufacture, and the ready manner 90 in which they can be assembled, make my invention more serviceable and available than any now on the market.

Referring now to the accompanying drawings, which illustrate an embodiment of my 95 present invention in a preferred form:—Figure 1, is a top plan view of a listing machine constructed in accordance with my invention, the printing attachments being removed to show the item and total dials in position for 100 printing, and the top broken away to show the arrangement of the key shafts and counter shafts and their connections. Fig. 2, is a longitudinal vertical section through x—x, Fig. 1, only one of the sets of arms and levers 105 connecting the counter rock shafts to the key operated shafts and registering dials being shown to avoid confusion. Fig. 3, is a transverse horizontal section along the line y—y, Fig. 2, showing in plan the operating mechanism for both sets of registering dials. Fig. 4, is a top plan view of the two sets of regis- 110

tering dials with the top of the casing removed, part of the item dials being broken away to illustrate in the plan the resetting mechanism therefor. Fig. 5, is a detail view 5 of the resetting mechanism for the item dial in side elevation looking to the left. Fig. 6, is a front elevation of the counter rock shafts and the bearing plates therefor. Fig. 7, is a detail rear view of part of the transfer devices 10 for the total dials. Fig. 8, is a detail side elevation of an operating lever for the total dial resetting mechanism. Fig. 9, illustrates the total dial resetting mechanism in longitudinal side elevation. Fig. 10, is a detail 15 plan view of the printing attachments, the paper rolls being shown in dotted lines. Fig. 11, is a front view of Fig. 10, illustrating the manner in which the printing carriage is mounted on the machine frame. Fig. 12, is a 20 vertical section through the printing attachment and a portion of the dials looking to the left, and showing the mechanism in the act of printing an item. Fig. 13, is a reverse side elevation of the printing attachments looking 25 to the right and illustrated with a printing carriage shown slightly lifted on its pivots from its slide supporting carriage. Fig. 14, is a detail illustration of the pivot connection between the printing and slide frames. Fig. 30 15, is a detail view of part of the slide frame broken away to show the stops to limit the travel of the printing devices.

Similar reference numerals refer to similar parts throughout the drawings.

35 My improved listing machine comprises a casing having front and back sections 1 and 2, and a top 3. The front portion of the casing contains the key operating mechanism which comprises a plurality of keys arranged in any 40 desired number of rows of nine each extending from front to rear of the machine. The number of rows of keys is determined by the capacity of the machine, that illustrated being provided with seven rows of numeral keys. The keys of each row are provided 45 with finger pieces 4, which are numbered consecutively from 1 to 9. These keys have shanks 5 which project through suitable openings in the top and in a guide plate 6 mounted on bars 7 and supported near the bottom of the casing on angle irons 8 secured to front 1, and a transverse partition 9. Supports 10 brace the bars 7 near their centers. The key shanks are reduced near their inner 55 ends leaving shoulders 11 between which and plate 6 are disposed coiled springs 12 surrounding the shanks and acting against the shoulders to return the keys to initial position. Pins 13, carried by the shanks, serve 60 to stop the upward movement of the keys by engaging the top. Each key shank carries a pin or antifriction roller 14, adapted to engage an arm 15 on a rock shaft 16. Each 65 row of keys has a corresponding rock shaft provided with nine rocker arms 15, one for

each key, which are rigidly connected to their respective shafts and project therefrom at different angles to and on the same side of a longitudinal vertical plane through each shaft. Each of these arms is adapted to be 70 engaged and rocked a determined distance by one of the keys, being so arranged that each receives an annular rocking movement determined by the value of the key depressed. Thus the keys of a row will give 75 their respective shaft nine annular rocking positions representing registering points in its travel, each key increasing the movement imparted to the shaft in equal steps. All the 80 keys of a row have strokes of uniform length 85 but the point in their downward travel where they engage and act on their rock shaft 16 varies. This is an improvement over arrangements which require the keys to be depressed different distances, as this materially affects speed of operation. To provide for the closer arrangement of parts, the rollers 14 are disposed alternately on opposite sides of the key shanks of successive rows, so that the arms 15 operated by the "6" or "7" keys are 90 staggered. The shafts 16 are journaled at one end to the front 1 of the casing which carries coiled springs 17 connected to the shafts and adapted to return them and their connected parts to initial position after operation. Transverse bars 18, connected to the sides of the casing, serve as intermediate bearing supports for the shafts, whose other ends are journaled in the partition 9, through which they project and are rigidly connected 100 to arms 19 which engage stops 20, also carried by the partition, which serve to limit their movement due to the action of springs 17. Through the agencies described, the shafts 16 may be independently rocked in their 105 bearings a distance proportioned to the value of the keys which operate them, and returned by the coiled springs 17, this rocking motion being transmitted from the arms 19 to the registering mechanism by the devices which will now be described. A plurality of counter rock shafts 21, corresponding in number with the rock shafts 16, are journaled in bearing plates 22 and 23 connected to the sides and bottom of the frame 115 and braced together at their upper ends by a cross plate 24. The shafts 21 are preferably of varying length, the shortest being uppermost, and are arranged so as to bring the right hand ends of the several shafts opposite their corresponding rock shafts 16, while the left hand ends of these shafts terminate more closely together for the purpose hereinafter described. The bearing plates 22 and 23 may be formed of one piece, 120 but as shown they are separate plates, stepped or shouldered so as to separate their oppositely disposed portions different distances corresponding with the lengths of the shafts 21 which are journaled in apertured 125 130.

lugs 25 turned at right angles to the plates. Each shaft 21 carries at its right hand end a crank arm 26 disposed opposite its corresponding rock shaft 16, and adapted to be moved thereby through an arm 27 swivelly connected to the arm 19 on said rock shaft. By these means each rocking movement of a shaft 16 serves to rock a corresponding shaft 21 in its bearings, which rocking movement 10 is transmitted to the item and total dials in the following manner.

I mount an arm 28 intermediate its ends on the left hand end of each shaft 21. These arms are rigidly connected to the shafts and 15 disposed adjacent to a bearing lug 25 of plate 22, on the inside thereof, so that the rear ends of the arms will project between the bearing plates. These arms are normally disposed at an incline, as seen in Fig. 2. 20 Loosely journaled on the same end of each of the shafts 21 on the outside of the bearing lugs 25, is an arm 29 (Fig. 3) which projects towards the front of the machine and has its end bent to the right and connected to a 25 vertical arm 30, the lower end of which is disposed above and adapted to be engaged by the lower front end of the adjacent arm 28 carried by the same shaft. By this means the arms 29 may be moved upwardly by the 30 direct action of the shafts 21 through the arms 28, but their return downward movement is made independently of the return movement of the latter arms. The purpose of this is to enable the item wheels 31, which 35 are operably connected to the arms 29 by arms 30, to be moved from initial position by the direct action of the key operated mechanism, but to be independent of such mechanism in returning to initial position.

40 The registering mechanism, as seen in Figs. 1 and 4, is assembled at the left side of the rear end of the casing and in order to dispose the registering dials or wheels at the most convenient point to be operated by the 45 mechanism described, I arrange them above the set of arms 28 and 29 which, by the construction and arrangement of their respective shafts 21, are disposed in the same planes with the registering dials which they 50 operate. As the item and total dials are of considerable diameter, I prefer to dispose them in a registering compartment formed as a vertical extension of the casing. A front plate 32 connected to the top 3, extends upwardly in a double curve to form the front 55 of the registering compartment. This plate is connected on one side to a plate 33 supported by the top 3 and constituting the right side of the compartment whose other 60 sides are formed by extending the adjacent side wall 34 and the rear wall 2 of the casing upwardly to a level with plates 32 and 33. A top plate 35 is connected to the walls of the compartment and overlaps the sides 65 thereof as seen in Fig. 11. The several item

dials 31 are loosely mounted on a shaft 36 between washers 37 keyed in position thereon and are provided each with a spacing shoulder which engages the adjacent dial. The shaft is journaled in the plate 33 and 70 wall 34. These dials are cut away across their lower portions and provided with pins or studs 38 to which their operating arms 30 are pivotally connected. By thus reducing the thickness of the dials I provide for the 75 free play of these arms between them.

The item dials on their under sides are each provided with a set of nine teeth 39, one for each digit. A pawl 40, held by a spring 41 against the dial teeth, is pivotally connected 80 to each of the vertical plates 42 mounted on a base 43, which is supported upon two bars 44 supported upon the partition 9 and connected at their rear ends to a second vertical partition 45 adjacent to the rear end of the 85 casing. The several spring pressed pawls 40 engage the teeth on the item dial so as to prevent the return movement of the dials to their initial position after being moved to indicate an item. The reset mechanism to 90 the item dials will be hereinafter described.

On its periphery opposite the teeth 39, each dial is provided with two sets of digits running from 0 to 9. The lower set of digits are printed, stamped or fixed upon the 95 periphery of each dial in any desired manner and are disposed so that they are visible through a glass covered sight opening 46 in the front 32 of the registering compartment. The upper set of digits are to be used for 100 printing items and are therefore in the form of type, as best seen in Fig. 4, and secured to the periphery of the dials in any suitable manner. They are so arranged relatively to the printing devices hereafter described, that 105 the type digits corresponding to the digits visible through the sight opening 46 will be disposed in a position to print the item seen through said opening. In my present construction I show the item dials 31 arranged 110 so that they project slightly above the top 35 of the registering compartment through an opening therein.

In addition to the seven item dials 31, one of which is provided for each row of number 115 keys, I provide a printing dial 47, having a flanged periphery of sufficient width to receive the type for printing a desired set of words. This dial is operated in the same manner as the item dials by a row of printing 120 keys at the left of the bank, which, by means of the transmission devices described for the sets of number keys, impart movement to the dial 47 setting it forward to nine registering positions, one corresponding with each key, 125 from its initial position where it does not print. This wheel is thus adapted to print nine words which may be such as are best suited to the character of work which the machine will be called upon to perform. As 130

illustrated I have adapted this wheel to designate the character of the items by printing opposite them abbreviations for the following words, exchange, discount, interest, cash, balance, note, deposit, draft, and check, the finger pieces 4 of the keys, which operate the printing dial, are respectively marked as follows, "Exc." for exchange, "Dis." for discount, "Int." for interest, "Cash.", "Bal." for balance, "Note", "Dep." for deposit, "Dft." for draft, and "Ck." for check.

The totaling mechanism comprises a set of eight totaling dials 48 (one in excess of the item dials 31), which are loosely journaled upon a shaft 49 mounted in the said walls of the registering compartment in the same manner as shaft 36 and on a horizontal plane therewith. These dials are preferably of the same diameter as the item dials and have their upper peripheries projecting above the top 35 of the registering casing through an opening therein. These dials are each provided with a plurality of sets of printing digits, running from 0 to 9 and arranged successively around the whole periphery. Being of the same diameter as the item dials, I arrange each set of digits so that they are subtended by the same arc as either set of digits on the item dials. As illustrated there will be four sets of printing digits on each total dial. A ratchet wheel 50, provided with a number of teeth corresponding with the digits on the total dials, is secured to one side of each total dial. Arms 51, one of which is swivelly connected to the rear end of each rocker arm 28, lead upwardly between the item and total dials and connect each to the outer end of a lever 52 loosely journaled on shaft 49. There will be seven of these arms 51, which will transmit motion from the arms 28 to the first seven total dials, counting from the right, by the engagement of spring pressed pawls 53 carried by the levers 52, with the teeth on the ratchet wheels 50. The eighth total dial being used only for carrying over from the seventh dial, will not be independently operated by the keys. The movement of the rocker arms 28, which corresponds with the value of the key which actuates them, will be thus transmitted by the arms 51, levers 52, and pawls 53 to the corresponding total dials, each of which will be advanced a number of registering points corresponding with the digit value of the key depressed in its corresponding rows of keys. As this movement will bring the successive sets of type digits in printing position, it is necessary to provide carrying mechanism to transfer from dial to dial as each new set of digits is brought into use by the rotation of the dials.

The transfer mechanism comprises a set of seven transfer levers 54, one of which is disposed adjacent to each total dial, except the first or units dial, and is provided with a cir-

cular reduced bearing end which overlaps a similar reduced bearing end of an oppositely disposed lever 52. By thus reducing and overlapping the adjacent ends of the pair of levers disposed between each pair of dials, 70 the dials may be arranged more closely together. The levers 54, which are loosely journaled on the shaft 49, project rearwardly and substantially horizontally, and carry spring pressed pawls 55 oppositely disposed 75 to the pawls 53 and in engagement with the ratchet wheels 50. At their outer ends these transfer levers are swivelly connected to arms 56 (as seen more clearly in Figs. 4 and 7), which in turn are swivelly connected to 80 the outer end of levers 57 pivotally mounted on the rear face of the plate 45. Springs 58, also carried by the plate 45, tend to draw the levers 57 and arms 56 downwardly against stop pins 59. A second arm 60 is connected 85 to each lever 57 at a point nearer its pivot. At their upper ends these arms 60 are each swivelly connected to a trip lever 61, pivotally mounted on studs 62 connected to the back 2 of the casing. At their free ends 90 these trip levers are adapted to engage pins 63 projecting from the side periphery of the total dials. There will be a pin 63 for each set of digits on each dial, the pins being placed so that as each digit 9 on a dial is 95 brought into printing position, a pin will engage the trip lever 61, disposed opposite to said dial, and, as the dial is moved forward one registering point to bring the zero digit of the succeeding set of digits into printing 100 position, the travel of the dial will be imparted to the trip lever and acting through arm 60, lever 57, arm 56, and transfer lever 54, this movement will be transmitted by the pawl 55 to the ratchet wheel 50 and will advance the dial wheel of next higher degree 105 one registering point. The trip levers are so disposed relatively to the pins that they are released from the pins after the latter have traveled one registering point. To compensate any slight lost motion and to the better insure a positive carrying action, the arms 60 are connected to the levers 57 nearer to the pivot points of the latter than the arms 56. These latter arms will therefore have a 110 travel slightly longer than that of the arms 60. Since the movement of the latter arms is derived from the dial from which the carrying is to be effected, it follows that the movement of the carrying levers 54, for the 115 dials of higher degree to which the carrying is to be effected, will have sufficient travel to insure the positive carrying of one digit. The springs 58 act to maintain the arms 56 and levers 54 and 61 in initial position until 120 their respective dials have reached the registering point. As there will be no lever 54 and pawl 55 to engage the ratchet wheel on the first or units total dial, I provide a spring 125 pressed pawl 64 mounted upon the plate 45 130

and adapted to engage the ratchet wheel to the units dial and hold it against movement in any but a forward direction:

The rocking movement imparted by the 5 keys to the shafts 16 and 21 will rock the arms 28 through an arc corresponding with the value of the keys depressed. The arms 28, through the arms 30, lift the item dials so that they exhibit through the eight opening 46, digits corresponding with the numbers of the keys depressed, and also set similar type digits in position above the top 35 to print the item. A corresponding registering movement is imparted to the total 15 dials through the arms 51, levers 52, pawls 53, and ratchet wheels 50, so that these dials are advanced a requisite number of steps to register the numbers of the operated keys. The coiled springs 17, connected to the shafts 20 16, are sufficiently strong to insure the prompt return of these shafts and also the shafts 21 to their initial position after they have been rocked by the depression of the keys. This return movement of the rock 25 shafts will be imparted to the arms 28, which will move the levers 52 for the total dials back to an initial position, these dials being held against reverse movement by the action of the pawls 55 and 64. It will be noted, 30 however, that since the arms 28 are not connected to the operating devices 30 for the item dials, these arms may swing downwardly without effecting a return of the item dials to their initial or zero position. After 35 an item has been registered the keys and total dial arms 51 will be promptly returned to initial position, while the item dials will be held, in registering position by the engagement of the pawls 40 with their respective ratchet teeth 39. To release these item 40 dials, I provide a special reset mechanism comprising a key 65 connected to a lever 66 pivotally connected to the left side of the case near the support for the pawls 40. At 45 its rear end the lever is provided with an elongated slot 67 which receives an end of a swinging bar 68 pivotally connected by links 69 to a journal pin 70, mounted in the plates 42. The rear ends of the pawls 40 project 50 over the bar 68 (Fig. 5) and are engaged and lifted thereby when the lever is depressed until they engage stop pins 71 carried by plates 42, and against which the springs 41 bear. This moves the several pawls, against 55 the action of their springs, out of engagement with the teeth 39, thus leaving the item dials free to be returned to their initial position which is effected by means of springs 72 supported by hooks 73 from the 60 front side of partition 45 and connected each to the rear end of a lever 74 fulcrumed between lugs or ears 75, preferably struck up from a bearing plate 76 fastened to the bottom and side of the casing. These levers 74 65 pass through openings in this plate 76 and

also through openings 77 (Fig. 6), in the bearing plate 22 for the rock shafts 21. At their forward ends these levers 74 are swivelly connected by links 78 to the arms 29 between their pivot points and forward ends 70 where they are connected by the arms 30 with the item dials. The springs 72 will therefore tend to draw the arms 30 downwardly and to return the item dials to initial position, the movement of the dials being 75 stopped when they register zero, by the engagement of the arms 30 with the ends of the levers 28.

To effect the return of the total dials to their initial or zero position, I provide the 80 mechanism illustrated in Figs. 8 and 9, and which comprises two bracket plates 79, loosely journaled on the shaft 49 on each side of the total dials. A similar plate 80 is loosely journaled on the end of the shaft, 85 which projects beyond the side of the main casing and carries a portion 81 of an operating handle disposed at its lower left hand end (Fig. 8). A rod 82 passes through an articulate slot 83 in the side wall of the casing and connects the lower front ends of the plates 79 and 80. A frame 84 has lugs 85 journaled on rod 82 and so disposed that the rear side of the frame is capable of sufficient vertical play to bring the studs 86 carried thereby, 90 into engagement with stops or pins 63 on the total dials. A portion 87 of the frame projects through the slot 83 and carries a half handle 88 opposite 81 but normally spaced therefrom the distance which portion 87 95 drops into a notch 89 in the lower edge of slot 83. A coil spring 90, connected to shaft 49 and engaging plate 80, tends to swing the reset mechanism to its initial position where 100 87 drops into notch 89 and holds the parts 105 until the handle parts 81 and 88 are drawn together. This not only frees the frame of the notch but also brings the stud 86 into position to engage the dial pins 63 as the frame is swung to the rear. The arc of 110 travel of the plate 84 corresponds with the arc subtended by a set of digits, and it therefore follows that each stud 86 will pick up a total dial, regardless of its position, and continue to advance it until the pins 63 on the 115 dials are brought into alinement and the dials set to a position where they will each print zero. It will be noted that the length of the studs 86 corresponds substantially with the depth of the notch 89 so that when the portion 87 rests therein, these studs will be out of engagement with the pins on the total dials, which will be free to operate without interference from the resetting mechanism.

The printing mechanism is disposed above the registering compartment whose top 35 overlaps the sides sufficiently to form guides for a sliding frame comprising two U-shaped slides 91 connected at their front ends by a 130

bar 92. The under side of one of the slides is notched, as seen in dotted lines Fig. 15, and a pin 93 in the top 35 engages the ends of the notch so as to stop the frame in a position where the printing roll is opposite either the item or total dials. The slides 91 extend beyond the rear wall 94 of the compartment, where they are each provided with a depending flange 95 to which flanges 96 on the bars 97 of the paper carriage are pivotally connected. This is best illustrated in Fig. 13, where the paper carriage is swung upwardly on the pivotal connection just described and lifted above the sliding frame. The paper carriage comprises the bars 97, which are connected at their front ends by a cross piece 98 adapted to rest upon the cross piece 92 of the sliding frame. Near their rear ends the bars are also braced by a second bar 99. Beyond the pivot point the bars 97 are bent and continue back to the front of the machine as arms 100. Thus an integral spring frame, V-shaped in side elevation, is provided, the front ends of the spring arms 100 being connected by a finger piece 101. The printing roll 102 and the guide rolls 103, on each side thereof, are journaled in the arms 100. A frame 104, between which the arms 100 are disposed, is mounted on the bars 97 and provided at its rear end with standards 105 which support the paper roll 106. The spindle 107, on which the printing roll is fastened, extends through slots 108 in the frame 104 and is provided on both ends 35 with finger wheels 109, by means of which the roll may be turned independently of its automatic feed mechanism. A plate 110 is loosely journaled on the spindle 107 at the left end of the printing roll and is provided 40 with an arm 111, which is held by a spring 112 against a pin or stop 113 carried by the frame 104. A dog 114 is pivotally connected to the plate 110 and held by a spring 115 in engagement with a ratchet wheel 116 45 rigidly connected to the printing roll. The spring 112 is connected to the spring arm 100, the operation being that as the spring arms are depressed to the position shown in Fig. 12, the spring 112 will act to hold the arm 111 against the pin 113 as the plate 110 is 50 drawn down, thereby causing the plate to rock on the spindle and move relatively to the ratchet wheel 116 so as to bring the dog 114 in engagement with the next ratchet teeth 55 to the right, Fig. 13. As the spring arms 100 move upwardly, the plate 110 will rock back on its axis and through the dog will advance the printing roll one step. Thus as the carriage is depressed for printing, the paper is 60 automatically fed around the printing roll from the roll 106, passing over the two guide rolls 103 and under the printing roll 102. The frame 104 is provided at each side with lugs or ears 117, in which are journaled 65 pulleys 118. Two flexible cords or chains

119, connected to the spring arms 100, pass over these pulleys and engage the frame 120, in which an inking roll 121 is journaled. At the center of its rear portion this frame 120 is connected to the spring 122 which is also 7 connected to the stationary bar 99. As the arms 100 are depressed the spring draws the inking roll to the rear, causing it to pass over the exposed type digits of either the item or total dials according to the position of the 7 printing carriage and ink them sufficiently to print when the printing roll strikes them. Since the normal position for the carriage will be that for printing the items, I provide the left hand slide 91 with a spring pressed 8 catch 123 having an end 124 bent up at right angles and adapted to engage the front end of the top 35 and hold the carriage in its front position. A finger plate 125 is connected to the frame 104 above the rear end of the catch 8 123 so as to provide a ready means for grasping and operating the latter when it is desired to shift the mechanism to its rear position for the purpose of printing a total. To prevent a reverse movement of the printing 9 roll, I provide it with a second ratchet wheel 126 at its right hand end, which is engaged by a pawl 127 pivoted to one of the spring arms 100 provided with an antifriction roll 128, which is held in engagement with the 9 ratchet teeth by a spring 129. I provide a paper cutter 130 disposed above the forward roll 103 and connected to the arms 100.

Having thus described my invention, what I claim as new and desire to protect by Letters Patent, is:—

1. In a machine of the character described, a casing a plurality of independent key operated members, registering devices, and operating means for said devices comprising a 1 plurality of rock shafts of different lengths which are operably connected to said key operated members, said rock shafts being disposed in different vertical planes with their corresponding ends stepped, as and for 1 the purposes described.

2. In a machine of the character described, a set of independent key operated rock shafts disposed longitudinally of the machine, registering devices, a set of rock shafts for operating said devices which are disposed transversely of the machine, and means to connect each of said transverse rock shafts with a corresponding key operated rock shaft.

3. In a machine of the character described, a plurality of independent key operated members disposed longitudinally of the machine, a plurality of rock shafts of different lengths, each of which is connected to one of said longitudinal members and operated thereby, registering devices disposed at one side of the machine, and means to operate said devices from said rock shafts in the manner described.

4. In a machine of the character described, 1

a plurality of key operated rock shafts disposed longitudinally of the machine, spring means to return said shafts to initial position, cranks connected to the ends of said 5 shafts, a corresponding number of transversely disposed rock shafts connected at one end to said cranks, registering devices, and means moved by said transverse shafts for operating said devices in the manner de- 10 scribed.

5. In a machine of the character described, a plurality of registering devices, a plurality of actuating members having their ends adjacent to said devices stepped, means for 15 operating said devices connected to the stepped ends of said actuating members, and key operated means to move said actuating members, substantially as described.

6. In a machine of the character described, 20 a plurality of transversely disposed rocking members disposed one above the other and increasing relatively in length from the top downward, means to support said members so that their corresponding ends terminate 25 closely together and in alignment with registering devices, means actuated by said ends of the members for operating registering devices, and key operated members connected to said transverse rocking members, sub- 30 stantially as described.

7. In a machine of the character described, a casing inclosing key operated means for actuating a registering mechanism, in combination with a compartment for said registering mechanism supported by said casing and disposed above it, a set of item dials and a set of total dials therein operably connected to the actuating means disposed below them in said casing and openings in said compartment through which said item dials are visible from the front and both sets of dials are exposed from above, as and for the purposes described.

8. In a listing machine, the combination 45 with item indicating devices and total indicating devices, of key operated members, each of which is operably connected by arms with an item and a total registering device, spring means to return said key operated members to initial position, and independent means to return said item devices.

9. In a machine of the character described, a plurality of item indicating devices, independent key operated members for actuating 55 said devices, means to return said actuating means to initial position independently of said registering devices, means to catch and retain said devices in the position to which they have been moved by said key operated means, and means to trip said catches and release said devices by the depression of a key lever.

10. In a machine of the character described, registering means comprising item 65 and total indicating devices, operating

mechanism for said devices comprising key actuated members, arms connecting each member with an item and a total device, means to return said members to zero position after actuating said devices, said arms for 70 operating the item devices being free of said members as they return to zero position, and independent means to control the release and return of the item devices.

11. In a machine of the character de- 75 scribed, item and total registering devices, key actuated members for operating said devices, means to connect said members and item devices which are moved in one direction by said members but are free to return inde- 80 pendently of said members to initial position, and means to operate said total devices which move with said members in both directions but are effective to move said total devices during their travel in but one direction. 85

12. In a machine of the character de- 90 scribed, a plurality of item and total dials, arms positively connected to the item dials, arms carrying pawls which engage teeth movable with the total dials, and key oper- 95 ated rocking members adapted to operate said arms substantially as and in the manner described.

13. In a machine of the character de- 95 scribed, sets of item and total dials, ratchet teeth on the total dials, a pawl carrying arm for actuating each of said dials, an arm for actuating each item dial, a plurality of rock shafts, key operated means to move said shafts, and levers connected to said shafts 100 and to the total dial operating arms, said operating arms for the item dials being engaged by said levers and moved thereby, substantially as described.

14. In a machine of the character de- 105 scribed, item and total dials, key operated rock shafts disposed below said dials and carrying lever arms, devices connected to 110 said lever arms and adapted to move said total dials in one direction, devices for moving the item dials in both directions which are moved by said levers in one direction, and spring means to return said latter devices to initial position independently of said levers.

15. In a machine of the character de- 115 scribed, a casing, item and total dials dis- 120 posed in said casing, openings in the top of said casings through which said dials project, type digits on the item and total dials ex- 125 posed by said top openings, a second set of indicating digits on the item dials, printing means mounted on said casing and co-operating with said type digits, and a sight opening in the front of said casing through which said indicating digits on the item dial are visible. 130

16. In a machine of the character de- 130 scribed, item and total indicating devices ar- 135 ranged adjacent to each other near the top of the machine and provided with type digits,

key actuated means disposed below said devices for operating them, means to hold said item indicating devices, when moved to register digits 9, out of operative engagement with said actuating means, and printing means disposed above said devices and operable independently of the key actuated means, said printing means being adjustable so as to print from said item or total indicating devices.

17. In a machine of the character described, item indicating devices, total indicating devices, key means for controlling the operation of said devices, and printing means adjustable so as to coöperate with either of said indicating devices to record items or totals and comprising a spring frame carrying a printing roll, means to feed paper around said roll, and a finger bar to depress said roll into engagement with said indicating devices, substantially as described.

18. In a machine of the character described, registering devices carrying type digits, and a printing means, coöoperating therewith, which is slidably mounted on top of the machine and adapted to be operated by hand, by the depression of a spring member spring means to move said printing means into position above one set of dials and a catch to hold said printing means in position above the other set of dials when moved there, substantially as described.

19. In a machine of the character described, a printing mechanism comprising a depressible member carrying a printing roll, means to automatically feed paper around said roll as it is depressed, a registering mechanism provided with type digits, means to cause an impression of said type digits to be taken on the paper around said roll when the latter is pressed against the registering devices, said printing mechanism being disposed at or near the top of the machine and adapted to be operated by hand independently of the registering mechanism.

20. In a machine of the character described, independent sets of item and total registering devices disposed in a separate compartment, a printing mechanism coöperating therewith and comprising a carriage mounted on said compartment so as to slide thereon, stops to bring said carriage to rest opposite said item or total devices, a spring member movable with said carriage and carrying a revoluble printing roll and a finger bar, and means to print items or totals on a strip of paper by adjusting said carriage and depressing said spring member.

21. In a machine of the character described, a casing, registering devices therein provided with type digits, a hinged frame slidably mounted above said devices and carrying a printing mechanism which is adapted to coöperate with different sets of said type digits, said mechanism comprising a paper

and a printing roll, and means to automatically feed said paper as the device is operated for printing for the purposes described.

22. In a machine of the character described, printing devices comprising a hinged frame supporting a paper roll, a spring frame mounted on said hinged frame and carrying a printing roll, registering devices provided with type digits, means to print from said type digits by the depression of said printing roll, substantially as described.

23. In a machine of the character described, a registering compartment having item and total type dials disposed therein and projecting above said compartment, printing devices slidably mounted on said compartment and comprising an inking roll, a paper roll, a printing roll, means to automatically feed the paper around said latter roll, and a finger bar for operating the printing devices by hand.

24. In a machine of the character described, printing devices coöperating with type bearing registering devices and comprising a spring pressed member adapted to be operated by hand, a printing roll carried by said member, means to pass the paper around said roll, and automatic feed devices for said roll comprising a member pivoted at one end adjacent to said roll and movable therewith, a stationary stop, spring means to force the free end of said member against said stop throughout its movements, a toothed element fixed to said roll, and a pawl carried by said member and engaging said element, for the purposes described.

25. In a machine of the character described, a plurality of key actuated rock shafts, item dials, arms connected to said dials, springs acting on levers connected to said arms and tending to move the dials to their initial position, and members fixed to said rock shafts which move said arms against said spring means by engaging said arms or parts movable therewith without being positively connected thereto.

26. In a machine of the character described, a plurality of total dials, a toothed element movable with said dials, a pair of oppositely disposed pawl bearing levers arranged between adjacent dials, said pawls acting to move said toothed element in the same direction, key actuated members for operating one of said arms, and means acted upon by the dials to move the other pawl bearing levers which coöperate with the dials of relatively higher order.

27. In a machine of the character described, a compartment containing sets of item and total dials, a top for said compartment through which said dials slightly project and which overlaps the sides of said compartment, a frame mounted on said compartment, and having sides which overlap the sides of said compartment top, spring means

to hold said slide in one position, a V-shaped spring frame hinged at its apex to said slide, a printing roll journaled in the upper arm of the spring frame, a finger bar carried by said arm; and means to pass paper around said printing roll, as and for the purposes described.

28. In a machine of the character described, item and total indicating devices, 10 key controlled means adapted to simultaneously advance both item and total devices, means to catch and hold said item devices in the position to which they have been thus advanced, leaving said key controlled means

tree to return independently thereof to initial 15 position, said item devices when advanced to their extreme positions being held out of operative engagement with said key controlled means, and means to restore said item devices to operative engagement with 20 said key controlled means.

In testimony whereof I have hereunto set my hand in presence of two subscribing witnesses.

JAMES FRANCIS MAYS.
